UNITED STATES PATENT OFFICE.

LOUIS P. ROSE, OF ARNOLD, NEBRASKA.

LINOLEUM-VENDING MACHINE.

Application filed June 29, 1926. Serial No. 119,338.

The invention relates to linoleum vending machines and has for its object to provide a machine conveniently arranged to display linoleum and like material in rolls when placed on sale by dealers handling the same.

A further object is to provide a linoleum roll rack on which is rotatably mounted a horizontally disposed shaft which supports a roll of linoleum and an expandible member carried by a stand adjacent the rack, and around which expandible member linoleum is wrapped for vending and measuring purposes, and after the vending and measuring operation said expandible roller is contracted, thereby allowing said roller to be easily removed from the roll of linoleum.

A further object is to provide an expandible linoleum roller comprising a tubular member having a plurality of longitudinally disposed convexed members adjacent the tubular member and having link connections with the tubular member and which link connections, upon movement towards one end of the tubular member, move the longitudinally disposed members outwardly to a position where they will form a roll of a predetermined size, and when moved inwardly will contract the device thereby allowing the expandible roll as a whole to be easily moved from a roll of linoleum.

A further object is to provide a flanged sleeve slidably mounted and keyed on the tubular member and having link connections with the expanding links for controlling said expanding links. Also to provide a sleeve having right and left hand thread cooperating with the flanged sleeve and a member on the tubular member, and forming means whereby said flanged sleeve can be easily moved for expanding or contracting the device.

A further object is to provide a gripping strip having supports extending through elongated openings in one of the expanding members and cooperating with said expanding member for gripping the end of a piece of linoleum.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:

Figure 1 is a vertical longitudinal sectional view through the expandible roll.

Figure 2 is a side elevation of the expandible roller, the rack and the adjacent roll support.

Figure 3 is a side elevation of one of the expandible roller supports.

Figure 4 is a vertical transverse sectional view taken on line 4—4 of Figure 1.

Figure 5 is an enlarged longitudinal sectional view through the controlling means of the expandible roller.

Referring to the drawing, the numeral 1 designates a rack having a horizontally disposed shaft 2 on which a roll of linoleum is placed for display purposes, however several rolls may be placed on the same rack if desired for display purposes. Disposed adjacent the rack 1 are vertically disposed standards 4 in bearings 5 of which the ends of a longitudinally disposed tubular member 6 are rotatably mounted, and from which bearing the ends of the tubular member 6 may be easily removed through the upper end thereof. One end of the tubular member 6 is provided with a crank 7 adapted to be grasped by the operator during the rotation of the device.

Pivottally connected at 8 to the tubular member 6 is a plurality of pairs of crossed links 9, the outer ends of which are pivotally connected to shaft 10 carried by the inner sides of the convexed longitudinally disposed plates 11, which plates are adapted to be moved inwardly and outwardly as desired. When moved outwardly one of said plates 11 moves towards the inner side of the gripping plate 12 which is supported on standards 13 carried by the tubular member 6, and between which plate 12 and the member 11 the end 14 of the linoleum is gripped and held whereby upon the rotation of the expandible roller linoleum from the roll 3 will be wound onto the expandible roller for vending purposes, and during which rolling operation, the material may be measured. After the desired amount of linoleum is wound onto the expandible roller when in expanded position 105 the roller is removed from the standard 4 and then contracted which will release the gripping action of the plate 12 and allow the roller to be easily removed from the roll of linoleum and replaced on the standard 4.

Pivottally connected to the rods 10 are links 15, which links extend towards one end of the

tubular member 6 and are connected at 16 to the flange 17 of a threaded sleeve 18. The sleeve 18 is slidably keyed on the tubular member 6 and rotates therewith. Disposed 5 on the sleeve 6 is a second sleeve 19 having a flange 20 which engages the standard 4 and threaded on said sleeves is a rotatable member 21, which is provided with right and left handed thread cooperating with right and 10 left handed thread carried by the sleeves 18 and 19, therefore it will be seen that the sleeve 18 will be moved axially inwardly and outwardly according to the direction of rotation of the member 21 for expanding or 15 contracting the roller.

From the above it will be seen that an expandible and contractible roller is provided for linoleum rolls which roller is simple in construction, positive in its operation and 20 may be easily and quickly expanded and contracted as desired. It will also be seen that during the expanding operation the gripping plate 12 will be moved to operative position for gripping the end of the linoleum.

25 The invention having been set forth what is claimed as new and useful is:—

1. An expandible linoleum roll comprising spaced supports, a tubular member rotatably mounted in bearings of the support, a plurality of longitudinally disposed outwardly movable parallel strips adjacent the periphery of the tubular member, links carried by 30

said strips and pivotally connected to the tubular member, said links being in crossed relation, a longitudinally movable threaded sleeve mounted on the tubular member, links connected between said sleeve and the strips, a second sleeve mounted on the tubular member, opposed threads carried by said sleeves, a longitudinally disposed stationary gripping strip to the outside of one of said first named strips, means carried by the gripping strip and extending through elongated openings in one of the strips and anchored to the tubular member, one of said first mentioned outwardly movable strips cooperating with the inner side of the gripping strip upon outward movement, and a member threaded on said sleeves and forming means whereby one of said sleeves is axially moved. 45

2. The combination with an expandible roller comprising a shaft, longitudinally disposed outwardly and inwardly movable strips carried by said shaft, of a gripping strip, one of said movable strips upon its outward movement cooperating with the inner side of the gripping strip and rigid members carried by the gripping strip and extending through elongated apertures in one of the strips and connected with the shaft. 50

In testimony whereof I hereunto affix my signature.

LOUIS P. ROSE.
